UNITED STATES PATENT OFFICE.

WILLIAM MORRISON, OF TROY, NEW YORK.

METHOD OF MAKING BRUSHES.

1,265,237.

Specification of Letters Patent. Patented May 7, 1918.

Application filed October 19, 1914. Serial No. 867,437.

To all whom it may concern:

Be it known that I, WILLIAM MORRISON, a citizen of the United States, and a resident of Troy, county of Rensselaer, and State of New York, have invented a certain new and useful Improvement in Methods of Making Brushes, of which the following is a full, clear, and exact specification.

This invention relates more particularly to a method of making an improved form of brush as disclosed in the patent of John Morrison No. 843,544, issued February 5, 1907. In accordance with this patent a brush is formed with a back having a plane surface, and a thick coating of plastic material carrying protruding tufts of bristles, the coating being mounted on the back of the brush by the use of adhesive substance which is rendered sticky when subjected to heat. A brush capable of withstanding considerable usage is difficult to produce in this manner owing to the adhesive substance not being sufficiently durable to cause the plastic material to adhere properly to the back, and moreover as the plastic material is exposed in this form of brush it may be easily damaged when subjected to water as well as being susceptible of collecting dust and other foreign matter which cannot be readily removed therefrom.

My invention is designed primarily to overcome these objections by providing a brush consisting essentially of a back having a plane surface, and a plate of plastic material carrying protruding bristle-tufts. The plastic plate is fixed on the plane surface to the back by a binding layer of waterproof adhesive substance in which is incorporated a quantity of coarse sawdust, or particles of cork, or granules of other insoluble material to provide crevices so that the plastic plate will firmly adhere thereto whereby all tendency of the plate to separate from the back will be obviated.

Another object of the invention is to provide on the exposed surface of the plastic plate a covering of waterproof material in order to allow the brush to be readily cleaned when desired, as well as preventing water from contacting with the plastic plate of the bristle-tufts; and a further object of the invention is to provide a brush of simple and efficient form, and which may be made to sell at a very moderate price.

The method consists in coating the flat face of the back of the brush with adhesive

material, securing granular material to the flat face of the brush back by the adhesive material to form a roughened surface for the said back and allowing the material to harden, embedding bristles in a cementitious plate and applying the cementitious plate to the brush back while the plate and adhesive material are in a comparatively soft state for securing the plate to the back.

In the drawing, Figure 1 is an inverted plan of the back of one form of brush embodying my invention.

Fig. 2 is a top plan of the perforated metallic covering used in the brush, and

Fig. 3 is a section taken longitudinally through the brush when the parts thereof are assembled.

The brush back 10 may be made of any suitable material in any desired shape and size, and while I illustrate in the drawing the invention as being carried out in the form of a hair brush, it will be understood that the brush may be fashioned in types adapted for various purposes. One face of the back 10 has a plane surface, as at 11, thereby dispensing with the recessing as is incident to many forms of brushes of this class, and which adds considerably to the expense of manufacture.

On the plane surface 11 of the back 10 is applied a binding layer 12 of an adhesive substance, such as shellac which is commonly known as being practically impervious to water, though it is soluble in alcohol and a number of other solvents, as well as being rendered sticky by the application of heat thereto. The adhesive binding layer is first converted to a liquid state by a suitable solvent, or by heat, and the liquid is then applied by any suitable means to the plane surface 11 of the back. In practice it has been found that the binding layer when formed of an adhesive substance in this manner its exposed surface is too smooth, and in order to produce a rough exposed surface thereon in the layer while its substance is still in a soft state is incorporated a quantity of coarse sawdust, or particles of cork, or granules of other insoluble material, as 13, though instead of this process the granules of insoluble material may be incorporated in the adhesive substance before it is applied to the back if desired, so as to protrude from the surface of the layer. By providing the surface of the binding, or adhesive layer with

the protruding particles of insoluble granules 13 irregular crevices, as 14, are formed in the exposed surface of this layer.

On the rough surface of this binding or adhesive layer 12 of the back is a plate 15 of cement, or other plastic composition in which is embedded by the customary means a number of rows of bristle-tufts 16, and this composition may be made according to 10 any of the formulas well known in this art, all of which are capable of hardening through the process of cementation. The composition plate 15 is fixed to the adhesive layer 12 by forcing the plate thereon under 15 suitable pressure while the layer and the plate are in a comparatively soft state. The composition will then enter the crevices 14 between the protruding granules 13 of the layer, and the plate 15 will be firmly held thereto against accidental displacement.

As the composition plate 15 is liable to be affected by water when subjected thereto, as well as readily collecting when in 25 use particles of dust and other foreign matter which is removed with great difficulty, on the exposed face of plate 15 is a covering 17 of thin sheet aluminum, or other metal, or celluloid, or other material 30 which is ordinarily waterproof and dust-proof so as to be readily cleaned, and this covering has a number of perforations 18 therethrough. The perforated covering 17 is slightly larger in diameter 35 than the composition plate 15 so that the edge thereof will protrude beyond the edge of the plate, and this covering is applied on the composition plate before the bristle-tufts are embedded therein, the covering 17, 40 composition plate 15, and the bristle-tufts 16 being assembled by the usual means employed in the manufacture of brushes of this class. When the composition plate, the cov-

ering, and the bristle-tufts are assembled and applied to the back 10, as above described, the edge of the covering will also be forced into the adhesive layer 12 whereby water and other fluid as well as foreign substances will be prevented from contacting with either the composition plate, or 50 the adhesive layer. In this manner a brush of unusual durability and one which may be easily cleaned may be cheaply made.

In the foregoing description, I have embodied the preferred form of my invention, 55 but I do not wish to be understood as limiting myself thereto, as I am aware that modifications may be made therein without departing from the principle, or sacrificing any of the advantages of this invention, 60 therefore I reserve to myself the right to make such changes as fairly fall within the scope of the appended claim.

Having thus described my invention, I claim as new and desire to secure by Letters Patent:—

The herein described method of making brushes having a back with one of its faces substantially flat, consisting in coating the said flat face with adhesive material, securing granular material to the flat face of the brush-back by the adhesive material to form a roughened surface for the said back and allowing the adhesive material to harden, embedding bristles in a cementitious plate 75 and applying the cementitious plate to the roughened surface of the brush-back while the plate and adhesive material are in a comparatively soft state for securing the plate to the said back.

This specification signed and witnessed this seventeenth day of October, A. D. 1914.

WILLIAM MORRISON.
